AXMINSTER LOOM

William W. Robertson, Northboro, Mass., assignor to Crompton & Knowles Loom Works, Worcester, Mass., a corporation of Massachusetts

Application December 16, 1935, Serial No. 54,650

11 Claims. (Cl. 139—9)

This invention relates to improvements in Axminster looms and it is the general object of the invention to provide an improved control motion for tuft yarn guide plates.

5 This application is a continuation in part of application Serial No. 688,308, filed by me September 6, 1933.

In Patent No. 1,958,129 issued on an application filed by Dacey and myself and copending 10 with application Ser. No. 688,308 there is shown a series of guide plates mounted in front of the reed and below the nose board together with control mechanism to project the plates rearwardly into substantial alignment with the reed dents so 15 that the tuft yarns extending from the tube frame can be guided into the reed spaces during the tuft forming operation. In that application the plates and the frame which carries them are mounted to swing about a single center, requiring a close setting to place the plates low enough to 20 clear the weft laying needle without losing their alignment with the fingers of the nose board.

It is an important object of my present invention to provide a control for the plates which will 25 modify the simple arcuate motion of the structure shown in said application so that during the first part of their rearward movement the plates are sufficiently high to guarantee registry with the nose board, but during the latter part 30 of the movement they will move down to clear the needle. This general result can be accomplished by the mechanism set forth hereinafter, including two centers about each of which the plates may move. The first of the centers may 35 be so located as to give the plates a rising motion at the beginning of the rearward stroke, while the second is so located as to cause the plates to move in a path lower than that along which they would have traveled had they continued to 40 move about the first center. This result I may accomplish by placing the second center in front of the first, but I do not wish to be limited to this construction.

With these and other objects in view which 45 will appear as the description proceeds, my invention resides in the combination and arrangement of parts hereinafter described and set forth.

In the accompanying drawings, wherein a convenient embodiment of my invention is set forth, 50 Fig. 1 is a vertical longitudinal section of an Axminster loom having my invention applied thereto.

Fig. 2 is a view similar to a portion of Fig. 1 on an enlarged scale showing the reed in forward position.

Fig. 3 is a view similar to Fig. 2 but with the parts in different position and indicating in dotted lines how the guide plates effect their downward movement.

Fig. 4 is a front elevation taken in the direction of arrow 4, Fig. 2, and

Fig. 5 is a horizontal section on line 5—5 of Fig. 2.

Referring particularly to Fig. 1, the loom frame 10 is provided with a breast beam 11 for the cloth 10 C. A transporting chain 12 brings a series of tube frames to delivery position one at a time, one of said tube frames being indicated at 13. Transfer mechanism indicated generally at 14 operates first to disconnect a tube frame from the 15 chain by pivotal movement of a lever 15 about a center 16, after which the lever 17 which supports the center 16 may be lowered about center 18. The tube frame has yarn tubes 19 from 20 which project the tuft forming yarns Y. Mechanism not shown herein but substantially the same as set forth in the aforesaid application may be employed to rock the tube frame so as to wipe the color yarns into position between the 25 binder threads B and B'.

Front and back cutters 20 and 21, respectively, operate to sever the tufts from the tube frame after the latter has been raised in the pulling-off operation. The lay 25 is provided with a series of reed dents 26 and is supported on a lever 27 30 oscillatable about a shaft 28 supported by the loom frame. A link 29 is connected to the lower end of the lever 27 and is operated by cam points 30 to move the reed back and forth. A nose board 32 is provided with a series of separated 35 rearwardly projecting teeth 33 each having a hook 34 and a rear inclined yarn manipulating surface 35. The matter thus far described may operate substantially as is common in the usual Axminster loom, or as set forth in the aforesaid 40 patent.

My invention relates to devices which align the tuft yarns with the spaces between the reed dents and is illustrated herein in connection with guide plates 40 mounted on a bar 41 which as 45 shown more particularly in Figs. 2 and 3 is carried at the upper end of a support 42. Operating links 43 are pivotally connected as at 44 to this support and are actuated by arms 45 on a shaft 46 turning in fixed bearings. A link 47 reciprocated by cam 48 and lever 49 therefore is 50 operatively related to the shaft and rocks it to raise the links.

The support is bolted as at 50 to levers 51 each 55 of which is pivoted to a stud 52 carried by a lever

53. Each lever 53 is pivotally supported at 54 to a bracket 57 bolted to the underside of the breast beam. Levers 53 move about fixed pivots and each is preferably provided with a roll 55 mounted for engagement with a surface 56 concentric with the lay axis 28. This surface may be part of the hub of the lay supporting lever 27, if desired. The fixed pivots 54 are in alignment and mounted independently of the lay, although the relation between the lay axis and pivots 54 remains constant. The levers 51 are all actuated by cam 48 and arranged across the length of the loom.

Each lever 51 has a lug 61 through which passes a bolt 60, and each bolt passes down through a lug 63 which is a forward extension of the corresponding lever 53. A heavy spring 62 is provided for each bolt and lies between lug 63 and nuts 65 on the bolt. A stop finger 66 on lug 61 is normally held against a second stop finger 67 on lug 63 by expansion of spring 62. These fingers can be filed to effect desired adjustment.

When in normal position the plate manipulating parts assume the relative position shown at Fig. 2, the rolls 55 being raised from the surface 56 and the springs 62 being expanded. The plates 40 are located forwardly in the spaces between the fingers 33 and are therefore aligned with the reed dents which also enter these spaces.

The operation of the tube frame and lay and other parts of the loom may be the same as set forth in the aforesaid application. During this operation, which need not be set forth in detail herein, the plates are moved rearwardly so as to align with the reed dents. When moving rearwardly the plates 40 should not interfere with the lower warp shed B'.

Starting with the plates forward and the roll 55 above surface 56, the links 43 will rise, swinging levers 51 and 53 about the fixed axes 54, moving plate 40 rearwardly until they reach the fell of the cloth, or from the position of Fig. 2 to the full line position of Fig. 3. The fingers 66 and 67 are held together by springs 62 during this movement. Rolls 55 then engage the surfaces 56, after which further movement in a clockwise direction, as viewed in Fig. 2, on the part of the levers 53 will be prevented. Thereafter, continued upward movement of the links 43 will cause levers 51 to swing around centers 52, lugs 61 moving away from lugs 63 to compress springs 62. This movement of plates 40 about axes 52 will cause them to move from the full to the dotted line position shown in Fig. 3 along a path lower than a continuation of the curve along which the first part of their rearward motion take place. The tops of the plates therefore do not project substantially into the shed defined by the binders 60 and there is consequently no opportunity for said plates to interfere with the weft or weft laying mechanism N when the plates are in their rearmost position. When so placed, however, the plates are effective to perform their tuft yarn guiding functions. During the latter part of the motion of the plates the rolls 55 withstand the pressure of the springs 62, and the lay will be in its rear position, as indicated in Fig. 3.

As the plates begin to move forwardly from their rearmost position the springs 62 will hold the lever 49 against the cam 48, and as the latter turns to permit downward movement of the links 43 each finger 66 will approach the associated finger 67. When contact between the fingers oc-

curs, they will move as a unit about the axes 54, the rolls 55 being raised from the surfaces 56.

A spring 70 may be attached to the connections which are operatively related to the lever 49 and the support 42 to insure downward movement of the bar 41 and return of the plates 40 to their forward position, and also hold lever 49 against cam 48. As will be understood from Figs. 2 and 3 the greater part of the weight of this structure is offset from a vertical line passing through either of the centers around which the plates to their normal forward position hence use of the spring 70 is optional.

I have set forth herein only enough matter to show how the plates can be operated and it is to be understood that the remainder of the mechanism can be controlled as desired, for instance, as in the aforesaid application.

From the foregoing it will be seen that I have provided simple and efficient means for giving the plates a modified motion, said means moving the plates during the first part of their rearward movement in such a direction as will preserve their alignment with the nose board and therefore the reed dents, after which said means completes the backward movement of the plates by requiring them to move downwardly to clear the weft laying mechanism, the guiding of the plates by the nose board being preserved. The specific mechanism shown herein causes the plates to move about two centers one preferably in advance of the other.

Having thus described my invention it will be seen that changes and modifications may be made therein by those skilled in the art without departing from the spirit and scope of the invention and I do not wish to be limited to the details herein disclosed, but what I claim is:

1. In an Axminster loom operating with a reed and having warp threads to define a shed, yarn guiding plates, means to move said plates in a direction toward the shed, and means to continue the movement of the plates toward the reed in a direction to prevent said plates from entering the shed. 40

2. In an Axminster loom operating with a reed, a set of yarn guiding plates movable toward the reed, and successively operative means effective first to give said plates an upward movement toward the reed along one path and thereafter a downward movement toward the reed along a different path. 45

3. In an Axminster loom operating with a reed and having warp threads to define a shed, a set of yarn guiding plates, means to move said plates along an arcuate path which enters the shed, and means to cause the plates to move along a second arcuate path which lies below the first path, whereby said plates are prevented from entering substantially into the shed of the loom. 55

4. In an Axminster loom operating with tube frames having tuft yarns and having warps to define a shed, a set of yarn guiding plates, means to project said plates rearwardly along a relatively elevated path to cooperate with the tube frame to align the yarns, and means thereafter to continue the rearward movement of the plates along a path which is depressed with respect to the shed. 60

5. In an Axminster loom having a nose board 70 and a set of guide plates held in alignment by said nose board with the loom reed, means to move the plates rearwardly toward the reed relatively to the nose board and in guiding relation with respect to the latter, and additional means 75

effective as the plates continue their rearward movement to cause said plates to move downwardly.

6. In an Axminster loom having a nose board to align yarn guiding plates with the dents of the reed and operating with weft laying mechanism, means to move the plates toward the reed, and two separate devices to control the direction of movement of said plates, one of said devices giving the plates a general upward movement and the other of said devices operative after the first and effective to give said plates a general downward movement to clear the weft laying mechanism.

15 7. In an Axminster loom operating with a reed and having a nose board and weft laying mechanism, a set of yarn guiding plates normally in forward position and held by the nose board in alignment with the reed, means defining two separate centers about each of which said plates are movable toward the reed, and means to cause said plates to move first about one and then the other of said centers.

8. In an Axminster loom operating with a reed and having a nose board and weft laying mechanism, a set of yarn guiding plates normally in forward position and held by the nose board in alignment with the reed, means to give said plates two characters of motion toward the reed, the first being an upward and rearward movement to preserve alignment with the nose board.

and the second being a rearward and downward movement away from the weft laying mechanism.

9. In an Axminster loom operating with a reed and having warp threads to define a shed, a set of guide plates for the yarn normally in forward position, means to give said plates an initial rearward movement toward the reed along a path which enters the shed, and means to alter the latter part of the motion of said plates to cause the same to move along a path below the first path to keep said plates from entering substantially into the shed.

10. In an Axminster loom, a reed, tuft yarn guide plates, a tube frame having tuft tubes movable to positions between the plates to place tuft yarns between the plates, weft laying mechanism to lay weft behind the tube frame, and means to move the plates along two paths, one toward the tube frame and the other away from the weft laying mechanism.

11. In an Axminster loom operating with a reed and having warp threads to define a shed, a tube frame having yarn tubes, a set of yarn guiding plates under the warp threads spaced to receive the yarn tubes between them, and means to move said plates rearwardly toward the reed along two arcuate paths, the first of which when projected enters the shed, and the second of which lies below the first path.

WILLIAM W. ROBERTSON.
